UNITED STATES PATENT OFFICE.

PETER O. SOLIE, OF PORTLAND, DAKOTA TERRITORY.

CUT-OFF VALVE.

SPECIFICATION forming part of Letters Patent No. 327,902, dated October 6, 1885.

Application filed March 27, 1885. Serial No. 160,307 (No model.)

To all whom it may concern:

Be it known that I, PETER O. SOLIE, of Portland, in the county of Traill, Dakota Territory, have invented a new and useful Improvement in Cut-Off Valves, of which the following is a full, clear, and exact description, reference being had to the accompanying drawings, forming part of this specification, in which—

10 Figure 1 represents a plan view of a valve-chest with my improvements attached. Fig. 2 is a sectional view showing position when the slide-valve opens the steam-port. Fig. 3 is a like view showing position when slide-valve is nearly at end of stroke. Fig. 4 is a similar view showing position when slide-valve is at end of stroke and steam cut off.

15 My invention relates to slide-valves; and it consists in a device adapted to be attached to the slide-valves of steam-engines, which cut off the steam from the cylinder on any part of its stroke, thus permitting the use of steam expansively, which effects a great saving of fuel for the engines.

20 25 To enable others skilled in the art to make and use my invention, I will now proceed to describe the exact manner in which I have carried it out.

Some of the engines now in use employ 30 steam expansively; but the valve-gears connected therewith are very complicated and expensive, and for these reasons are not extensively used. By the use of means herein shown and described I am enabled to provide 35 a simple device capable of attachment to the common slide-valves of almost any engine, and dispensing with the costly valve-gears referred to.

In the said drawings, A represents a valve-chest of any well-known form, and composed 40 of any suitable material. The valve-chest is also provided with steam-ports *a' a'* and exhaust-port *b*, as shown in Figs. 2, 3, and 4.

B represents a slide-valve of ordinary construction, and operating in the usual manner. The valve B is attached to one end of the valve-stem C, the opposite end of the stem being connected to a suitable eccentric (not shown) on the engine, which operates the valve to open 45 or close the ports.

Secured to the valve-chest A, and passing longitudinally through the same, is a rod, D, provided with transverse projections or stops

5 *d d'*, which engage a vertical rod, *e*, and operate the cut-off attachment, as I shall hereinafter describe.

The slide-valve B is provided on its upper surface with an enlargement, *c*, to which is pivotally secured the cut-off attachment E. This attachment consists, essentially, of the longitudinal bars *g' g*, which are pivotally secured to the slide-valve and the transverse bars *h' h*, the general shape of the attachment conforming to the size and configuration of the valve. The longitudinal bar *g'* has projecting upwardly from its surface a pin, *e*, adapted to engage the stops *d*, before described.

From this description it is manifest that when the valve-stem C is moved it carries 70 with it the slide-valve and also the cut-off attachment. Just as the piston has nearly made its full stroke, and the port *a* has been uncovered, the pin *e* on the cut-off attachment, coming in contact with the stop *d*, causes 75 one end of the attachment to be thrown downward and closes the port *a*. This position is maintained on the return-stroke and until the port *b* has been uncovered, and the pin *e* strikes against the stop *d'* and closing the port 80 *b*, as in the former case.

Having thus described my invention, what I claim as new, and desire to secure by Letters Patent, is—

1. The combination, with a slide-valve, of 85 a rectangular frame or cut-off device pivoted thereto at or near its center, a pin secured to the cut-off, and suitable stops adapted to rock the cut-off to close the ports, substantially as herein described.

2. A cut-off attachment pivoted to and inclosing a slide-valve and suitable stops for changing the position of the cut-off and thereby close the ports, substantially as herein described.

3. The valve-chest A, provided with a valve-stem, C, a rod, D, and suitable stops *d d'*, secured thereto, in combination with a slide-valve, B, and inclosing cut-off pivoted thereto, and a pin, *e*, adapted to engage the stops, substantially as and for the purpose described.

PETER O. SOLIE.
